UNITED STATES PATENT OFFICE.

CHARLES EDWARD SHIFFER, OF WILMINGTON, DELAWARE.

FUEL-FEED SYSTEM.

Application filed October 14, 1921. Serial No. 507,635.

The present invention relates to new and useful improvements in systems for delivering liquid fuel in a gaseous state to an internal combustion engine of either the mobile or 5 stationary type, and while this invention is described in its particular embodiment as applied to a high speed automobile engine it should be remembered that the present illustration is but one specific embodiment and 10 that the system itself is equally applicable to low speed engines.

The primary object of the present invention is to provide a system of fuel supply whereby a greater amount of energy may be obtained from a given quantity of gasoline and 15 specifically a system whereby an increased power may be obtained from an automobile engine, together with a greatly increased mileage per gallon of gasoline.

20 A second object of the present invention is the provision of an auxiliary air intake directly connected to an automatically controlled throttle, thereby permitting the use of an air bubbling carburetor omitting entirely the

25 much-used needle valve carburetor. A further object of the present invention is to provide a device of the character described in which the individual parts will be simple to manufacture and easy to keep in order so that 30 the entire apparatus necessary to practice the system will be of simplified construction and operation, and one which, owing to its automatic operation, will be practically fool-proof when once adjusted by a capable mechanic.

35 Other objects of the present invention lie in the specific details of construction herein-after described and specifically set forth in the claims.

Figure 1 is a side elevation of an embodiment of my invention.

40 Fig. 2 is a sectional elevation of the control mechanism.

Fig. 3 is a plan view thereof.

45 Fig. 4 is an elevation of the control mechanism.

Fig. 5 is a view of the air valve.

The ordinary gasoline tank 10 normally supplied as part of the automobile is used with but two slight changes, one the provision 50 of a hole 11 to accommodate the air intake pipe 12 which is open at its lower end 14 beneath the level of the gasoline in the tank and is closed at its upper end by a spring pressed air intake valve 15, this valve being operated 55 from the engine, and, the other the provision of an opening 17 into which is fitted a short

section of pipe 18 leading to the gas chamber 20 which is merely a small auxiliary receptacle intended to hold gasoline-laden air acting as a dome for the tank so that no liquid gasoline shall be drawn through the pipe 22 leading to the manifold. The gage 23 is extremely convenient to prevent overfilling of the gasoline tank 10 and should be provided if not furnished by the automobile manufacturer.

The auxiliary air device consists generally of a cylindrical section of pipe 25 having a smaller branch 26 leading from one side thereof and being joined to the pipe 22 leading from the gas receptacle or chamber 20. The cylinder 25 is provided with an elliptical flange 28 whereby it is secured to the manifold and has an internal flange 29 at a point somewhat below the junction of the branch 26, this flange acting as a stop for the disk valve 30 which is held in place by a spring 31 surrounding the valve stem 33 and bearing against the cap 34 which closes the bottom of the cylinder 25.

70 The disk valve 30 is preferably made adjustable and consists of a member 40 rigidly secured to the stem 33 and an exactly similar member 41 which is adapted to move through a small arc about the axis of the stem 33 and of the disk 40 and to be held in adjusted position by means of a set screw 43 carried by the member 40 and working through an arcuate slot 44 cut in the member 41 so that by tightening the screw 43 the members 40 and 41 may 75 be permanently secured in the desired angular relation to one another so as to close the openings 47 in the member 40 to the desired degree.

75 Auxiliary air passes through the elongated openings 50 into the cylinder 25 and up to the manifold through the segmental openings 47 as restricted by the upper disk 41. This is true even when the valve 30 is in its extreme upper position. As the stem 33 is drawn 80 downward (as hereinafter described) additional air is admitted to the upper portion of the cylinder 25 in proportion to the amount of downward movement of the valve 30. The stem 33 is secured to an angle member 55 which is operated by a Z-lever 56 on the throttle valve shaft 57, the angle 55 sliding through a guide in a lug 59 on the cylinder 25.

85 The butterfly throttle valve 60 is permanently secured to the shaft 57 as is also the 90 crank 61 which at its free end is pivotally connected to the rod 62 leading to the foot

- throttle. The crank 63, however, is loosely mounted on the shaft 57 having an extension 65 which overlies one end of the Z-lever 56 which is permanently secured to the shaft 57. Movement of the foot lever will directly operate the butterfly valve but will not affect the hand throttle link 64 while operation of the butterfly valve by the hand throttle is indirect and does move the foot throttle link. 10 The extending portion 65 bears against the end of the lever 56 and since both this lever and the butterfly valve are rigidly secured to the shaft 57 the valve is opened when the lever is moved.
- 15 As previously stated the Z-lever 56 is rigidly secured to the shaft 47 and bears at one end against the upper portion of the angle 55, the angle being held against the lever by the spring 31. The actual contact, in order to 20 secure the proper adjustment, is had with the cap 67 which is threaded to the angle member 55 and this cap may be revolved on the angle member so as to properly adjust the movement of the valve 30. At its free end the Z- 25 lever 56 rests against the point of an adjusting screw 68 threaded in a lug 69 on the branch 26 so as to adjustably limit the movement of the butterfly valve in one direction.

The operation of the device is believed to 30 be clear from the foregoing description. On the suction stroke a vacuum is produced in the pipe 25, branch 26, pipe 22, chamber 20, and tank 10. This causes air to enter through the valve 15 and to bubble through the liquid 35 gasolene in the tank 10. The mixture of gasolene vapor and air passes to the chamber 20 and is drawn through the pipe 22 to the engine cylinder.

Should a back fire occur the gravity acting 40 valve 70 closes the chamber 22 and the force of the explosion opens the valve 30 which it will be seen serves as a safety valve in addition to its normal function as an auxiliary air valve. When the operator increases the 45 speed of the automobile by opening the throttle the auxiliary valve 30 is likewise operated admitting additional air through the elongated openings. Upon closing the throttle the spring 31 restores the valve 30 to closed 50 position at which time, however, air is admitted to the pipe 25 through the segmental openings 47.

What I claim is:

1. In combination, a fuel feed system for 55 automobiles, a combustible mixture outlet, a primary mixture passage leading thereto, a check valve between the passage and outlet, a throttle valve in said passage, an auxiliary

air inlet, a spring-pressed valve normally closing said inlet but free to open said inlet upon back-fire, and means connecting said valves so that the air valve is opened whenever the throttle valve is opened and is closed by its spring upon closing of the throttle valve.

2. In a control mechanism, a mixture outlet pipe, an air inlet pipe leading thereto and having a plurality of longitudinal slots therein, a primary mixture passage discharging to said mixture outlet pipe, a throttle valve in said passage, a check valve permitting discharge from the primary mixture passage to the mixture outlet but preventing fluid from passing in opposite direction, a spring-pressed valve in said air inlet normally held nearer the mixture outlet than said slots and manually controlled means for opening the throttle valve and simultaneously pressing the air inlet valve against its spring to a position to uncover a part of said slots.

3. In combination, a mixture outlet, an air inlet and a primary mixture passage each discharging to the mixture outlet, a check valve providing a one-way passage from the primary mixture passage to the mixture outlet, a valve in said air inlet, a throttle valve in the primary mixture passage, a hand throttle rod, an accelerator rod, and means for connecting said rods to said throttle whereby movement of the hand throttle rod will operate the accelerator rod, the throttle and the air inlet valve and movement of the accelerator rod will move the throttle and the air inlet valve, but not the hand throttle rod.

4. In combination, a mixture outlet passage, a mixture passage and an air passage connected therewith, a check valve at the end of the mixture passage and openable toward the outlet passage only, said valve being so positioned that the closure thereof is unaffected by air passing through the air passage, a throttle valve in the mixture passage and a valve controlling the air passage and means for simultaneously operating the last two named valves.

5. In combination, a tubular member, constituting an outlet passage having air openings at one end, a tubular fuel passage communicating with said member and extending thereto at an angle such that its open end is directed away from said air openings, a check valve governing the fuel passage and opening into the outlet passage, a valve controlling said air openings and a throttle valve controlling the fuel passage.

CHARLES EDWARD SHIFFER.
